BROOM HEAD OR THE LIKE

Robert J. Lindstrom, Sedalia, Mo.

Application April 29, 1957, Serial No. 45,927

Term of patent 14 years

(Cl. D9—2)

Fig. 1.

Fig. 2.

Fig. 3.

Fig. 4.

Fig. 1 is a perspective view of a broom head or the like embodying my new design, with a fragmentary portion of the handle shown in broken lines for illustrative purposes only;

Fig. 2 is a side elevational view thereof;

Fig. 3 is an end elevational view thereof; and

Fig. 4 is a top plan view thereof, with a portion of one end broken away for convenience of illustration only.

I claim:

The ornamental design for a broom head or the like, as shown and described.
